UNITED STATES PATENT OFFICE.

THOMAS J. JAMESON, OF FLORIN, CALIFORNIA.

TIRE.

1,294,108.

Specification of Letters Patent. Patented Feb. 11, 1919.

Application filed August 28, 1918. Serial No. 251,302.

To all whom it may concern:

Be it known that I, THOMAS J. JAMESON, a citizen of the United States, residing at Florin, in the county of Sacramento and State of California, have invented certain new and useful Improvements in Tires, of which the following is a specification.

This invention relates to new and useful improvements in pneumatic tubes for pneumatic tires and the primary object is to provide a tube of this character which will not become deflated when punctured.

The invention also aims to provide a tube which includes a plurality of intercommunicating air containers as differentiated from the single air container found in the ordinary pneumatic tube, thus making it possible to retain air in a majority of the air containers when one or more of them are punctured or otherwise rendered unfit to retain air.

Another object of the invention is to provide a series of circumferentially spaced air compartments or containers possessing sufficient resiliency to act in the capacity of a pneumatic tube and having a series of connecting elements adapted to automatically act to close the ends of two of the tubes adjacent one which becomes defective or punctured.

A further object of the invention is to provide a device of this character which consists of comparatively few parts and is simple in construction, but durable and well adapted to withstand the rough usage to which devices of this character are ordinarily subjected.

For a full description of the invention and the advantages and merits thereof reference is to be had to the following description and accompanying drawings, in which:

Figure 1 is a fragmentary side elevation partly in section, of a wheel showing my invention applied thereto.

Fig. 2 is a perspective view of one of the air containers.

Fig. 3 is a detail perspective view of one of the resilient valve protectors.

Fig. 4 is an enlarged detail section through one of the coupling valve members.

Referring to the drawings, wherein is illustrated the preferred form of my invention, in which like numerals of reference indicate corresponding parts throughout the several views, the shoe or tire A has

mounted therein a plurality of air containers 1, one of which is shown in detail in Fig. 2 of the drawings. Each air container is of tubular formation and of comparatively short length, although it will be obvious that the length of each container may be varied under different conditions and a greater or less number of containers may be provided if found desirable. Each air container one is adapted to occupy a segmental portion of the space within the tire and consequently conforms to the curve in the tire as shown in Fig. 1. Each air container is also constructed of rubber similar to the material from which the ordinary pneumatic tubes are constructed and consequently is inherently resilient when filled with air. The end of each air container is closed by an end wall 2 which has a centrally located relatively small opening 3 to permit intercommunication of the containers when mounted within the tire. One of the containers must be provided with an ordinary inlet valve 4 extending through the rim of the wheel in the usual manner so that an air pump may be attached to supply air to the containers when the device is to be inflated.

Interposed between the adjacent ends of two of the air containers is a coupling valve member shown in detail in Fig. 4 of the drawing. An exteriorly screw threaded sleeve 5 is provided at one end with an annular flange 6 which is to be mounted within the tube and have the sleeve portion extend outwardly through the opening 3 in one end of the air container. This causes one face of the flange to engage the end wall 2 and in order that the flange may be snugly engaged with this wall, the surface thereof is corrugated to form the ridges or ribs 7. It will be noted by referring to Fig. 4 that the sleeve 5 is not screw threaded throughout its entire length but the portion extending through the opening 3 in the end wall 2 of the air container is smooth and has a complementary washer 8 mounted thereon which engages the outer face of the end wall 2 and is provided with corrugations forming the ribs 7 so that the two series of ribs 7 and 7' will co-operate to tightly engage the end wall when the flange and washer are mounted in operative position. To bind the washer 8 against the end wall of the air container, a retaining nut 9 is provided on the screw threaded sleeve 5, this nut being 130

formed with a series of circumferentially spaced recesses 10 adapted to receive a wrench or the like whereby the nut may be tightened on the sleeve to force the washer 8 into engagement with the end wall of the air container whereby the latter may be tightly held between the flange and the washer 8. In this manner the end of the air container is tightly connected to one end 10 of the coupling member. The proximate end of the adjacent air container is connected to a complementary coupling element 11, the portion 12 of which is extended through the opening in the end 15 of the container from the interior thereof, whereby the flange 13 which is also provided with corrugations 14 will engage the inner side of the end wall of this air container. This coupling member 11, however, has a 20 relatively small screw threaded stud 14 adapted to be received in a screw threaded opening 15 in the end of the sleeve 5 so that the sleeve 5 which forms one of the elements of the coupling member can be securely connected to the element 11. The portion 12 of the coupling element 11 is also provided with a complementary washer 16 similar to the washer 8 which coöperate with the flange 13 to tightly engage the corresponding end 25 wall 2. This washer 16 is held in operative position by another nut 17 identical with the nut 9 and this nut 17 is also mounted on the screw threaded portion of the sleeve 5. In the end of the screw threaded stud 14 a space 30 18 is provided and this space, together with a space 19 in the sleeve 5, forms a valve receiving space for a spherical valve 20. A passage-way 21 in each valve member 5 and 11 establishes communication between the 35 interior of the two adjacent air containers through the valve space which receives the valve 20. Each passage-way 21 has a relatively large recess portion forming a shoulder against which one end of a coil spring 40 rests and the opposite ends of which engage the spherical valve member 20. Since these springs at opposite sides of the valve member are of equal tension, it will be obvious that the valve member 20 will be normally 45 held in the center of the recess so that air is permitted to pass through the passage-ways 21 and into the adjacent end of the air containers. At diametrically opposite points, however, the valve member 20 is provided 50 with the valve stem adapted to extend into either of the passage-ways 21 when the valve is moved in either direction. When this occurs, the valve also closes the entrance to the enlarged recesses in which the springs 55 are mounted so that the double valve seats are thereby provided to receive the valve member 20 according to the direction in which it is moved.

A relatively large flexible rubber disk 22 60 is mounted between the washers 8 and 16

and the nuts 9 and 17, it having a central opening within which the nuts are arranged. This washer of the shape shown to advantage in Fig. 3 of the drawings is tapered toward its periphery and acts as a protector 70 for the valve and coupling members when mounted in position.

Assuming that a series of air containers or compartments are connected together as shown in Fig. 1 by the coupling members, it 75 will be understood that the valve members 20 are disposed centrally as they are so held by the springs on either side of each valve. By attaching an air pump to the inlet valve 4, the air may be supplied and should be pumped 80 with a slow and even pressure so that the valves 20 remain in their neutral positions permitting the air to pass through all of the connecting passage-ways so that each air container will be inflated and placed under 85 the required pressure. When all of the air containers are thus inflated, the device will act in the same manner as an ordinary inner tube and will resiliently support the vehicle mounted upon the wheels with which 90 the invention is used. Now, should any one of the containers be punctured, the air in this particular container will immediately rush out through the container and since the air in the adjacent air containers tends to 95 rush toward the punctured air container, it will be obvious that the corresponding valves 20 will act to close the passage-ways to the punctured container, thus holding the air in all of the other containers. The slight re- 100 duction in air pressure will not affect the other air containers and the operator of the vehicle need not stop to make repairs. It will be obvious that several of the air containers may be punctured before the tire will 105 become entirely deflated.

Also, it will be noted that after one or more of the air containers are punctured, additional air may be supplied to the remaining air containers without making re- 110 pairs to the punctured air containers, since the valve members will act to close the ends of the punctured air container.

The foregoing description and accompanying drawings have reference to what might 115 be considered to be the preferred or approved form of my invention. I desire it to be understood that I may make such changes in the construction and combination of parts, materials, dimensions, et 120 cetera, as may prove expedient and fall within the scope of the appended claim.

Having thus fully described my invention, what I claim as new and desire to secure by Letters Patent, is:—

A pneumatic tube comprising a series of circumferentially spaced air containers, a coupling member interposed between the proximate ends of each adjacent pair of air containers, each coupling member provided 125

with a passage-way establishing communication between the air containers, the center of the passage-way being enlarged to provide a valve recess, a spherical valve 5 mounted in the valve recess, springs interposed between opposite sides of the valve to normally maintain the latter in the center of the said valve space, the said valve being adapted to close one end of the passage-

way to an adjacent air container when the 10 air is suddenly ejected from the latter.

In testimony whereof I affix my signature in presence of two witnesses.
